SUPPORT STAND FOR A BED SPREAD

Jonathan Ginat, New York, N.Y., assignor to Maurice Duchin Creations, Inc., New York, N.Y., a corporation of New York

Filed Oct. 16, 1964, Ser. No. 82,200

Term of patent 14 years

(Cl. D33—3)

I claim:

The ornamental design for a support stand for a bed spread, as shown.
